UNITED STATES PATENT OFFICE.

SAMUEL L. ALLEN, OF CINNAMINSON, NEW JERSEY.

CULTIVATOR.

SPECIFICATION forming part of Letters Patent No. 424,946, dated April 8, 1890.

Application filed November 7, 1889. Serial No. 329,528. (No model.)

To all whom it may concern:

Be it known that I, SAMUEL L. ALLEN, a citizen of the United States, residing at Cinnaminson, in the county of Burlington and State of New Jersey, have invented certain new and useful Improvements in Cultivators, of which the following is a full specification.

Referring to the accompanying drawings, Figure 1 is a side elevation of my improved cultivator. Fig. 2 is a plan view of the same. Fig. 3 is a section on $x x$, Fig. 2. Fig. 4 is a perspective enlarged view of the mechanism for adjusting the side bars. Fig. 5 shows in perspective the construction of the joint at the front of the handle-bars. Fig. 6 is a section through the central bar, handle-bars, and joint. Fig. 7 is a plan view of the cultivator as arranged for the banking of celery. Fig. 8 is a section in the plane $z z$, Fig. 7, showing the hinged connection of the forward end of the hillng-blades; and Fig. 9 is a section on $y y$, Fig. 7.

My invention consists of an improved cultivator having laterally and perpendicularly adjustable handle-bars and side bars adjustable laterally. It is, moreover, provided with hillng-blades interchangeable with said side bars, the parts being arranged in such a manner as to make the implement readily adaptable either for an ordinary tooth cultivator for growing crops of various kinds, or, when desired, for a celery or potato cultivator, to be used in banking or hillng them.

A is the central bar or beam, at the rear of which is bolted the tooth-standard K', bearing the tooth K.

B B are two detachable adjustable side bars, one on each side of the central bar, pivoted in front to the hinged plates F F', which are bolted to the bar A, one above and one below the bar, as shown in Fig. 1. These side bars B are provided with the ordinary cultivator-tooth standards bolted thereto and bearing the teeth B' B''. The handle-frame, composed of the handle-bars C C and the cross-pieces C', joining the same together, is laterally and perpendicularly movable about a joint at the forward end of the said handle-bars. To this end the central bar A is provided, preferably, with two substantially semi-cylindrical blocks P P—one on each side thereof—having the

tapered holes p. (See Figs. 5 and 6.) The forward ends of the handle-bars C are provided with plates P', rounded out to fit against the outer faces of the said blocks P, p' being the 55 fastening-bolt passing through the parts in the manner illustrated in Fig. 6, the arrangement being such that the handle-frame may be moved laterally about the central bar for some distance on either side, while it is held 60 quite stiff from torsional strain. The handle-frame is furthermore supported by the brace D, pivotally bolted at c to the sides of the handle-bars C, and the bottom of which rests upon the T-shaped bracket D', bolted either to 65 the rear tooth-standard K', as shown, or, if desired, directly to the central beam A. The front edge of the T-piece D' is provided with a series of notches d', and the horizontal portion of the brace D has a number of holes 70 d, (see Fig. 3,) so that the pieces D and D' may be bolted together with the fastening-bolt d³ through either of the holes d or notches d', according to the position of the handle-frame. It is then secured against horizontal, 75 perpendicular, or torsional change of position. When the handle-frame is centrally adjusted with reference to the cultivator-frame, as shown in the drawings, the said fastening-bolt d³ passes through the central hole d and 80 central notch d'. When it is desired to adjust the handle in a different position to one side or the other of the center, the thumb-screw d² is loosened, and the brace D swung forward on the bolts c as pivots to disengage the 85 bolt d³ from the notch d'. The handle-frame is then moved as far as desired around the joint P and the pieces D and D' again bolted together with the fastening-bolt in a different 90 notch or hole without removing the bolt from the hole d, but by simply loosening the thumb-screw d². This adjustment is very useful in vineyard and corn cultivation. The handles can be easily moved to avoid injuring the plants. In corn-covering, also, one need not 95 walk on the finished work. The handle-frame is, moreover, perpendicularly adjustable by reason of the series of holes c' in the top of the piece D, through either one of which the bolt c may pass.

Instead of the cylindrical joint shown at P, I may, if desired, employ a ball-and-socket

joint or a universal joint of any approved construction. I prefer, however, the arrangement here shown, in that with the cylindrical joint the connection is very firm against torsion, while the motion laterally is perfectly free.

As shown in Figs. 1 and 2, the implement is fitted with side bars B, having, as above described, ordinary cultivator-teeth. These side bars, however, may be detached, and in their place hillings-blades B³ or other attachments may be substituted, as hereinafter described, both the side bars B and the hillings-blades B³ being adjustable in the same manner.

15 The adjusting devices consist of a guide L, adapted to slide back and forth over the central bar A, the said guide having connected therewith the piece L', notched with teeth in the convex arc of a circle, as shown.

20 E is an open handle-lever fulcrumed at its lower end at e to each side of the sliding guide L.

O O are two links—one on each side—pivoted at o to the central bar A and at o' to 25 the lever E.

G G' are arms jointed together to form an elbow at g, and pivotally secured at g' to a rigid connection of the central bar A. The outer ends of the arms G' are pivoted at g² to 30 the rear of the side bars B.

H H are two side arms, pivoted at h to the sliding guide L, and having near the outer end of each one or more holes h², through either of which may be passed the hinge-bolt h', which 35 pivotally connects the said arm H to the arm G on each side of the implement, in a manner fully illustrated in Fig. 4.

The various arms and levers forming the link-motion for operating the side bars are so 40 proportioned and arranged that when the handle-lever E is moved back and forth the side bars B are moved in and out laterally in a manner easily understood by reference to Figs. 1 and 4, it being remembered that the 45 pivotal points g' and o are stationary, while the other pivotal points that enter into the combination—viz., e, g g', h h', and g²—are movable. This construction has been found to accomplish the lateral adjustability of the 50 side bars in the field in a very quick and easy manner.

Within the open handle-lever E is pivoted at e the secondary handle E', which operates, through the parts E² E³ and the spring E⁵, the 55 pawl E⁴, which engages with the teeth or notches on the curved piece L', so that the side bars B, when adjusted in the manner described, can be held in any desired position. As herein shown, the arms H have each two 60 holes h² for the reception of the pivotal bolt h', so that there are two ranges of adjustability of the side bars for a given range of movement of the handle-lever E, depending upon which of the two holes h² contains the 65 said bolt. Furthermore, by having one or more holes h² on each arm H, I am enabled to set one of the side bars nearer to the central bar

than the other, or, in other words, adjust the side bars unsymmetrically with reference to the central bar, when, as is often the case, it is desirable to throw more earth to one side than the other.

When it is desired to use the implement for the cultivation or banking of celery, potatoes, &c., it is simply necessary to substitute 70 for the side bars B the hillings-blades B³, which are interchangeable therewith. The side bars are removed by disconnecting the arms G' from the rear thereof and detaching and removing the hinge-plates F F', which are held by the bolts f f.

The hillings-blades are preferably constructed as shown in Figs. 7, 8, and 9. B⁴ is a cultivator hoe-tooth of suitable shape, whose standard B⁶ is secured by the fastening-plate 85 b⁴ or otherwise to the central bar A of the cultivator-frame. The tooth-standard B⁶ is provided with the piece B⁵, having two wings, to which are pivoted by the bolts b⁵ the blades B³, near the forward ends thereof. Near the 90 rear of each blade B³ is secured thereto, by means of the bolt b³, the piece G², having the slot g⁴ for the fastening-bolt b³, whereby the slotted piece G² may be varied in height. Like the side bars B, the celery-blades B³ are pivoted at g² to the arms G', the pivotal bolt 95 passing through the slotted piece G², as shown in Fig. 9, and the blades are adjustable laterally to varying widths of rows in precisely the same way as the side bars. In fact, these 100 celery-blades are in reality side bars and blades integral in one piece, the blades being made of such a shape that in connection with the front teeth or blade B⁴ the earth is banked up in sufficient quantity on the celery-rows on either side as the cultivator moves along.

I claim—

1. In a cultivator, the combination, with the central bar provided with a T-shaped 110 seat D', having notches d', of a pair of handle-bars jointed to said central bar, whereby they are laterally movable, and a standard D, pivotally secured to said handle-bars, and having a fastening screw and bolt engaging 115 with said notches, whereby the said handle-bars may be adjusted to various positions laterally without removing the said fastening screw and bolt, substantially as described.

2. In a cultivator, a central bar provided 120 with a notched bracket D', in combination with a laterally-movable handle-frame jointed to said central bar, and a brace D, pivoted to the handle-frame and provided with one or more bolt-holes, substantially as and for the 125 purposes described.

3. In a cultivator, the combination, with the central bar A, of a sliding guide L, a handle-lever E, fulcrumed in said guide, links O O, pivoted to the central bar and lever, hinged 130 side bars B, arms G G', pivotally connecting the side bars and central bar and having the elbow-joint g, and side arms H, pivoted to the said guide and to the arms G, all constructed,

arranged, and operating substantially as and for the purposes described.

4. In a cultivator, the combination, with the central bar and hinged laterally-adjustable side bars, of a link-motion, substantially as described, for operating said side bars, having arms H, each of which is provided with one or more holes h², substantially as and for the purposes described.
- 10 5. In a cultivator, the combination, with the central bar and hinged laterally-adjustable side bars, of a link-motion, substantially as described, for operating said side bars, having a sliding guide L, provided with a piece 15 L', notched with teeth in the convex arc of a circle, connected to and movable with said guide, an operating-handle E', and a pawl E⁴, engaging with said teeth and operated by

20 said handle, substantially as and for the purposes described.

6. A cultivator-frame having a central bar provided at its front end with detachable hinge-plates and a seat for a standard-fastening plate and having a sliding block or guide L L', a lever E, with spring-pawl E⁴, and expanding arms G G', operated by said lever, whereby provision is made for attaching side bars carrying shovels or teeth or for attaching a central tooth and hillng-blades, substantially as shown and described.

25 30 In witness whereof I have hereunto set my hand.

SAML. L. ALLEN.
